UNITED STATES PATENT OFFICE

ALAN M. OVERTON, OF CINCINNATI, OHIO, ASSIGNOR TO THE RICHARDSON COMPANY,
OF LOCKLAND, OHIO, A CORPORATION OF OHIO

BOX FOR REFRIGERATED SHIPMENTS AND THE LIKE

Application filed October 6, 1930. Serial No. 486,565.

My invention relates to improvements in boxes made of paper machine products for the shipment of fruit and other produce primarily, which containers have a body, a lid, and an outer ridge-forming member or cuff, the purpose of which is to increase the rigidity of the container and to space the bodies of adjacent containers from each other sufficiently to permit the circulation of air. 5 The latter function is of particular importance in the shipment of produce in refrigerator cars. The basic object of my invention is the provision of improvements in this type of container. More specific objects of 10 my invention are the provision of a new top construction and method of attaching it, together with improvements in the construction of the cuff and the attachment thereof.

These and other objects of my invention, 15 which will be pointed out hereinafter or will be apparent to one skilled in the art upon reading the specification, I accomplish by that certain construction and arrangement of parts, of which I will now describe a preferred embodiment, reference being had to the drawing which forms a part hereof.

In the drawing:—

Figure 1 is a perspective view of an open container showing one form of my cuff construction. 20

Figure 2 is a sectional view of a side of the container of Figure 1, showing the manner in which the lid is fitted to my box.

Figure 3 is a perspective view of a box 25 having a modified form of cuff construction.

Figure 4 is a sectional view of a side thereof.

Figure 5 shows the container of Fig. 3 30 fitted with my novel lid.

Figure 6 shows the blank construction for the lid.

Figure 7 shows the blank construction for the cuff of Figure 3.

Containers having sidewise projections or cuffs have been disclosed in an application of David T. Usher, Ser. No. 403,864, filed Oct. 31, 1929. In the box of this application the side members have projections which, along 45 suitable double-score lines, are bent back up-

on themselves and are stitched to the sides to form the said projections. Such construction necessitates the use of a lid or top which fits within the sides of the box. Flaps on the cover are thus not held within the box 55 by any direct acting force, except possibly a frictional engagement of the said flaps between the sides of the box and the contents. In the nature of the materials to be shipped in such boxes this pressure must be slight. 60 Consequently it is the practice to provide external means such as are shown in the said application hereinabove referred to for locking the cover in place. The locking means for the cover described in said Usher application may be employed with my box, although in one modification, I have provided other means for locking the cover. It is, however, an object of my invention to provide a box 65 and cover construction such that the box can be filled through the top thereof, and the cover can be placed in position, without inserting the flaps thereof between the fruit or other contents and the sides of the box, 70 whether or not the box is equipped with a 75 tray.

My box, while it may be constructed of other materials, is preferably made or comprises the felted product of a bituminous pulp, such as that described in the patent 80 to Stevenson and Buron, No. 1,771,150, of July 22, 1930. For the sake of strength and thickness a suitable board is usually made by pasting together two or more plies of paper machine product; and it is preferable 85 to make the said plies upon a multi-cylinder machine, the central vats of which are fed with the said bituminous pulp, the liner vats being filled with a pulp of fibers, which, while they may be sized, do not contain the bituminous binder substance. Several of such plies 90 may be cemented together or one of such plies may have liner plies of kraft or board cemented to it.

In the manufacture of my box, the body will usually be formed of a blank having scored portions to form the sides, an attachment flap which may be stitched to one of the sides, and flaps upon one end which are foldable over to form the bottom. I have 95

shown in Figure 1 a box having sides 1, and a bottom 2. The sides terminate upwardly in plain edges and do not have top forming flaps. I have shown a separate cuff 3 for each side which is held thereto by stitches 4. Each cuff is formed in one piece as shown in Figure 2 by running parallel scores down the center of a blank so that the blank may be bent into a U shape having a base 5, and legs 6 and 7. The legs are brought together and the cuff is stitched to the side of the box with the base 5 near the upper edge thereof, by stitches 4, which are located toward the outer ends of the legs. Thus the body of the cuff 10 is free from the side 1 of my box. A lid having a top portion 8 and a flap 9 may be placed on my box with the flap inserted, as shown in Figure 2, between the cuff and the side wall of the box where the said flap will be held by 15 frictional engagement.

For greater strength as well as a somewhat simpler manufacturing operation, I prefer to make my cuffs 3 all in one piece as shown at 10 in Figure 3. To this end I provide the blank shown in Figure 7 comprising outer cuff portions 11 articulated together by scores 12 which are wider than the scores used in forming the body of the box and may be, if desired, double scores. I provide also an 25 attachment flap 13 articulated to one of the members 12 by a score 14. Inner cuff members 15 are articulated to the members 11 by a wide or double score 16 and are separated by slots 17 wider than the double scores 12. In 30 use, the blank of Figure 7 is stitched into tubular form by attaching the flap 13 to the farthest member 11, the inner members 15 are folded inwardly, and the cuff member is placed on the box as shown in Figure 3, where 35 it is held by interspaced stitches 18 adjacent the lower ends of the members 11. In this construction the inner members 15 are shorter than the outer members so that the stitching is done through but one thickness of board 40 in the cuff and one thickness of board in the side wall. I prefer to use the one-piece cuff construction because it is economical of board. In the one-piece construction, as shown in Figure 4, there is a space between the body 45 of the cuff and the side wall of the box into which the cover flap may be placed and frictionally held. The cover flap may also be provided, if desired, with a projection which will interlock with the inner cuff member 15, 50 or I may provide a cover having the construction shown in Figure 6. Here I have articulated together by lines of scoring a lid portion 19, flap portions 20 and projections 21. In Figure 5 I have shown one of my boxes 55 with the stitches 18 so interspaced that the extension 21 may be passed down between adjacent stitches and between the cuff and the side wall as shown. As a further locking means I may provide slots 22 in the members 60 11 and I may score the projection 21 as shown

to provide tabs 23, which may be bent back over the cuffs and inserted in the slots 22, as shown in Figure 5, thus providing a positive lock.

In both modifications of my invention I have provided separate cuffs, which, where desired, may be colored without making it necessary to color the inside of the box body as has been necessary hitherto. I am enabled to use a separate cover which does not extend into the contents of my box. The lid may not be depressed further than the line of stitching 4 or 18 will permit the lid flaps to extend; and in that construction in which I have provided a locking method for the cover I am enabled to do away with wire hold downs or other external lock devices.

Having thus described my invention, what I claim as new and desire to secure by Letters Patent, is:—

1. In a container having a bottom and side walls, a separate cuff member comprising a piece of board bent upon itself and disposed with its folded portion adjacent the top edge of a side wall and stitched to said side wall by stitches passing through a lower edge of said cuff, said stitches interspaced to permit the passage of an extension of the cover flap between said cuff and said side wall so as to extend below said cuff.

2. In a container having a bottom and side walls, a separate cuff member formed of a piece of board bent upon itself and disposed with its folded portion adjacent the top edge of a side wall, said cuff member being stitched to said side wall by interspaced stitches passing through a lower edge portion thereof and a side wall, said stitches interspaced to permit the passage of an extension of a cover flap, a cover for said container, a cover flap on said cover and disposed in the space between said cuff and said side wall, and an extension on said cover flap extending beyond said cuff in the interspace between the stitches.

3. In a container having a bottom and side walls, a separate cuff member formed of a piece of board bent upon itself and disposed with its folded portion adjacent the top edge of a side wall, said cuff member being stitched to said side wall by interspaced stitches passing through a lower edge portion thereof and a side wall, said stitches interspaced to permit the passage of an extension of a cover flap, a cover for said container, a cover flap on said cover and disposed in the space between said cuff and said side wall, an extension on said cover flap extending beyond said cuff in the interspace between the stitches, and a slot in the outer member of said cuff, said flap extension being bent over and inserted in said slot.

4. In a combination with a container having side walls articulated by scores, a cuff member attachment to said side walls, said
